UNITED STATES PATENT OFFICE.

WASHINGTON I. PHIFER, OF COLLINSVILLE, ILLINOIS, ASSIGNOR OF TWENTY ONE-HUNDREDTHS TO PAUL PURDY STONE, OF DES MOINES, IOWA.

MECHANICAL MOVEMENT.

1,184,155.

Specification of Letters Patent. Patented Apr. 6, 1915.

Application filed May 19, 1913. Serial No. 768,398.

To all whom it may concern:

Be it known that I, WASHINGTON I. PHIFER, a citizen of the United States of America, residing in Collinsville, in the county of Madison and State of Illinois, have invented a new and useful Improvement in Mechanical Movements, of which the following is a specification.

One of the objects of this invention is to provide an improved construction of driving shaft for that type of engines which receive the impulse of the piston thrust on an inclined surface which is formed on the driving shaft.

Other and further objects will appear in the specification and be specifically pointed out in the appended claims, reference being had to the accompanying drawings exemplifying the invention, and in which,

Figure 1 is a vertical section of this improved engine. Fig. 2 is a transverse section taken on the line 11—11, Fig. 1. Fig. 3 is a view showing the explosion impulse receiving member to which the connecting rods are connected parts being shown in section. Fig. 4 is a side elevation of this improved driving shaft. Fig. 5 is a section taken on the line V—V, Fig. 4.

Referring to the drawings: 1 designates a series of cylinders which are arranged radially around a driving shaft 2. Surrounding said cylinders is the usual water jacket 3. Closing the outer ends of said cylinders are cylinder heads 4. Secured to the body portion 5 of said cylinders 1 is the housing 6, said housing being preferably of circular form having the end wall 7. Formed in the center of said end wall is a bearing 8 in which is mounted one end of the driving shaft 2, the opposite end of said driving shaft being mounted in the bearings 9 formed in the body portion of said cylinders. It is to be noted that the driving shaft 2 is composed of three parts, there being a part 10, the part 11, and the stud 12. Formed on the inner end of the part 10 is an inclined disk 13, and formed on the part 11 is a relatively inclined disk 14. Said disks are held apart by the enlarged central portion 15 formed on the stud 12, said stud holding the parts 10 and 11 rigidly connected by the nuts 16.

Mounted between the inclined disks 13 and 14 on the enlarged portion 15 of the stud 12 is an impulse receiving member 17

having the circular central body portion 18. Arranged radially around said body portion are a series of arms 19, said arms being equally spaced apart. Mounted on each arm 19 is a sleeve 20, each sleeve having formed therein a pair of oppositely opposed pins 21, a nut 22 is adapted to keep each sleeve 20 on its arm 19. Mounted on each sleeve 20 and each pair of pins 21 is a bearing 23, said bearing being formed on one end of the connecting rods 24. Each connecting rod is secured at its opposite end to the wrist pin 25 of the pistons 26. Said pistons are reciprocably mounted in the cylinders 1. Secured to the body portion 18 of the impulse receiving member 17 is a guiding finger 27, said finger being reciprocably mounted between a pair of guides 28 formed longitudinally of the interior of the bottom of the housing 6.

In the construction of the driving shaft, (from an inspection of Fig. 4) it will be noted that the parts 10 and 11 of said shaft will align lengthwise with the center line A. The disks 13 and 14 are formed on said parts 10 and 11, and are inclined at 45° from the central line A. The stud 12 which secured the parts 10 and 11 together passes through the disks 13 and 14 at right-angles thereto, being mounted in the central openings 29 formed in said disks, said disks being circular in shape. The longitudinal central line B of stud 12 will intersect at C with the line A at the center of the stud 12. The central line D drawn longitudinally between the disks 13 and 14 will also intersect the lines A and B at C.

In the operation of this improved engine, when in motion, the impulse of the explosions on each piston 26 will be directed to the disk 14 at a point as shown at E of Fig. 5, which is at a point to one side of the central line F. Therefore, inasmuch as the impulse receiving member 17 is held against revolving by the engagement of the finger 27 in the guides 28, the force of the explosion will be given to the inclined surface of the disk 14, which will cause the shaft 2 to revolve. When the piston 26 has reached the end of its stroke, it will be returned to the opposite end of the cylinder by the inclined face of the disk 14 engaging against the central body portion 18 as the shaft 20 is revolved. Each cylinder, as it is in turn

exploded, will give its exploding impulse against the disk 14 at the point E, and the exploding pressure will bear on the inclined face of said disk 14 to the point G of said disk. It is therefore seen how a series of exploding thrusts of the pistons and their connecting rods will be thrust against the inclined face of the disk 14, thereby driving the disk around. Said disk being a part of the shaft 2, said driving shaft will therefore be revolved. And as the impulse receiving member 17 is mounted between the disks 13 and 14, the disks 13 and 14 sliding around and against said member 17, there will be no lashing or knocking.

In order to provide lubrication to the working parts, a by-pass connection 30 is adapted to communicate from the water jacket 3 to the housing 6, being controlled by a by-pass valve 31. As the oil, which has been poured into the water surrounding the cylinders becomes heated by the exploding of the engine, the vapor arising therefrom will be oil-laden and will pass through the by-pass 30 into the housing 6. In order to further assist the lubrication of the working parts, splashing arms 32 are mounted on the shaft 2 inside of the housing 6, which arms will communicate with the oil at the bottom of said housing, thereby spraying the oil around the interior of said housing when the engine is in motion.

What I claim is:

1. A rotary member comprising a two-part shaft, an obliquely arranged disk secured to the adjacent ends of each part of said shaft, a stud mounted in said disks for holding the parts of said shaft in alinement, an impulse receiving member mounted on said stud between said disks, and connecting rods pivotally secured to said impulse member.

2. A rotary member comprising a two-part shaft, an obliquely arranged disk secured to the adjacent ends of each part of

said shaft, a stud mounted in said disks for holding the parts of said shaft in alinement, shoulders formed on said stud for holding said disks apart, an impulse receiving member mounted on said stud between said disks, and connecting rods pivotally secured to said impulse member.

3. A rotary member comprising a two-part shaft, an obliquely arranged disk secured to the adjacent ends of each part of the shaft, a stud mounted in said disks for holding the parts of said shaft in alinement, an impulse receiving member mounted on said stud between said disks, a series of radially arranged arms carried by said impulse member, and connecting rods pivotally secured to said arms.

4. A rotary member comprising a two-part shaft, an obliquely arranged disk secured to the adjacent ends of each part of the shaft, a stud mounted in said disks for holding the parts of said shaft in alinement, an impulse receiving member mounted on said stud between said disks, a series of radially arranged arms carried by said impulse member, sleeves mounted on said arms, and connecting rods pivotally connected to said sleeves.

5. A rotary member comprising a two-part shaft, an obliquely arranged disk secured to the adjacent ends of each part of the shaft, a stud mounted in said disks for holding the parts of said shaft in alinement, an impulse receiving member mounted on said stud between said disks, a series of radially arranged arms carried by said impulse member, sleeves mounted on said arms, a pair of oppositely disposed pins formed on each of said sleeves, and a connecting rod connected to each pair of pins on each of said sleeves.

WASHINGTON I. PHIFER.

In the presence of—

M. C. HAMMON,

H. G. FLETCHER.
